UNITED STATES PATENT OFFICE

CHARLES F. SIOBERG, OF YORK, PENNSYLVANIA, ASSIGNOR TO YORK SAFE & LOCK COMPANY, OF YORK, PENNSYLVANIA, A CORPORATION OF DELAWARE

CHEST DOOR AND CHEST STRUCTURE

Application filed February 18, 1929. Serial No. 340,934.

Incidentally to the rapid development of chain store systems and similar chains of oil and gasoline filling stations, moving picture theaters and the like, there is a large demand for burglar proof chests adapted to hold the collections made at the individual stores, theaters and stations, which chests or safes, as they are required in large numbers by the various individual organizations, must to 10 meet this demand, be manufactured and sold at a relatively small cost, and they further must for this trade be so constructed as to enable the proprietors to obtain insurance at preferential rates. The chests provided at 15 present for this purpose are not satisfactory in that when constructed to meet the requirements they are too expensive. The doors and the labor required to fit and mount the same, and particularly the hinges, are a considerable item of expense.

The present invention relates to a chest and to a door structure and details for mounting and securing the same whereby the use of hinges is avoided and the maximum of security and convenience is obtained at the 25 minimum of expense, the structure being one which can be produced in large quantities much more cheaply than any chest previously offered which is adapted to the same general purposes. The invention further provides for the normal retention of the door in mounted position without danger of accidental release and for the convenient removal of the door when open and it may provide double custody where it is found desirable, there being for this purpose an inner compartment so arranged that while it is partially accessible to the employees of the individual stores or stations who are acquainted with the combination in order that they may deposit the 30 money as collected, which is usually made into packages and introduced through a slot in the inner door, these deposits can be removed only by a person having the key to the inner door, usually a collector for the central organization who carries the key for this purpose.

Instead of a single inner compartment guarded by an inner door, the inner door may 50 be so arranged as to provide beyond the chest

door an outer storage space and an inner separately locked compartment. The chest door opening occupying preferably the top half of the front of the chest, the inner door may to advantage be arranged horizontally extending rearwardly below the chest door opening and being with its frame and support of an area substantially equal to the corresponding cross section of the chest, thus providing an outer storage compartment at the top of the safe and a separately locked compartment below.

In the drawings:

Figure 1 is a vertical section on the axis of the chest and door.

Figure 2 is a front elevation on a reduced scale, i. e., looking from the left in Figure 1 and showing the door closed.

Figure 3 is a top plan view of the door removed, the scale being the same as that of Figure 1.

Figure 4 is a rear elevation of the door removed.

Figure 5 is an elevation looking at the door from the right as seen in Figure 4.

Figure 6 is a fragmentary radial section of the door taken on the line 6—6 of Figure 4.

Figure 7 is a front elevation of the chest with the door removed.

Figure 8 is a similar elevation with the door closed showing the interengaging means on the door and chest body in dotted lines and a concrete setting for the same sectioned and broken away.

Figure 9 is a fragmentary section on line 9—9, Figure 7.

Figure 10 is a perspective of the front portion of the chest showing the door partially open.

Figure 11 shows in elevation the top portion of the chest at the front with the chest door removed and the inner door closed.

Figure 12 is a view corresponding to Figure 1, but fragmentary, showing the chest without the inner door.

Figure 13 is a vertical central section showing the inner door located in a horizontal plane extending rearwardly from a point near the bottom of the chest door opening, 100

dividing the chest into upper and lower chambers.

Figure 14 is a central horizontal section on line 14—14 Figure 13, illustrating the same construction and showing the inner door in plan, the chest door being removed.

Figure 15 is a front view on a reduced scale showing the chest door in the position of registration of the rib spaces and sections 10 and ready for removal, the front of the door being broken away to expose the ribs.

Referring to the drawings by numerals, each of which is used to indicate the same or similar parts in the different figures, the construction shown comprises a chest body 1, which may be of any preferred or convenient shape and provided with ears 2, by which it may be anchored in a suitable concrete structure or secured within a safe or similar enclosure in accordance with the prevailing practice. In order to obtain the benefits of the preferential insurance rates, the walls of the chest body should be made at least an inch thick of any suitable steel or steel alloy used for this purpose. The chest as shown is provided with a chest door opening 3, near the front end and spaced inwardly therefrom as shown, the opening 3 being shown as substantially semi-circular and slightly less than half the area of the chest door 4 and the door jamb opening to be hereinafter described. As shown, opening 3 occupies the upper half of the cross section of the chest being spaced slightly above the center with its straight side at the bottom of the opening. The chest door or main door 4 is of circular outline and preferably of one and one half inches or more in thickness throughout its area to comply with the requirements for the above mentioned preferential insurance rates. This main or chest door 4 is without hinges or similar supporting means, being mounted to rotate in a circular door jamb or seat 5 of corresponding size located outside the door opening 3 and within the end or end edge of the chest body 1.

The door may be rotatively secured in any suitable manner preferably the door jamb or seat 5 is formed with an annular inwardly disposed groove 7, the outer wall of which consists of a likewise inwardly disposed annular rib 8 and the door is formed as to its outer edge with a peripheral groove 9, which receives the rib 8, and the door is likewise provided with a peripheral outwardly projecting rib 10, forming the inner wall of groove 9 which rib engages and follows the groove 7 in the jamb or seat. The door 4 is supported and guided mainly in and by circular or short cylindrical seating surface 61 forming the outer portion of jamb 5. This surface is closely engaged by a corresponding cylindrical surface 62 on the door which guides and supports the door, said surfaces 65 being finished concentrically. The ribs 8 and

10 which with the contacting surfaces of the groove are also preferably finished, hold the door in this seat and to avoid machining between the rib sections to be described the chest body is hollowed out at 63.

To provide for the insertion and removal of the door 4, the ribs 8 on the jamb and 10 on the door, which will be hereinafter referred to as the inter-engaging members or ribs, are each of them interrupted or discontinued at intervals, so that the door being in closed position in which it may be locked, it may, having been duly unlocked, be rotated to full open position and the stop to be described being released, be then further rotated in the same direction to a position in which the arcuate portions of the rib 10 to be further described, overlie the spaces between the portions of the rib 8, permitting the door to be removed and replaced.

To provide for opening the door, the door or door member 4 is formed with an aperture 12 which is preferably semi-circular in outline as shown and adapted to register with door opening 3, being similarly shaped and located relatively to the center of seat 5 about which the door 4 rotates when mounted in the chest. The aperture 12 is shown as of a size somewhat less than half the area of the door 4 so that its arcuate edge 13 is conveniently spaced inwardly from the edge of the door providing a suitable marginal portion 14 to support the rib 10 or the arcuate sections thereof to be described. The flat side 15 or other portion of the aperture 12 in the door 4 which is nearest the center is also preferably spaced outwardly from the center of the jamb 5 and of the door. This opening 12 is thus practically of the same size as the door opening 3 and to open the door mounted as described it is rotated to bring the opening 12 in the door into registration with the door opening 3, see Figure 12. To close the door it is rotated 180 degrees from this position or through any suitable arc depending on the size and shape of the registering openings. The full closed position is illustrated in Figures 1 and 8. The exact relation of the door opening 3 and the open position of the door to the remainder of the structure is largely a matter of choice for convenience of access to the inside of the chest.

In addition to the grooves and ribs formed on the door jamb and the edge of the door already described, the door jamb seat 61 contains a stop groove 16 or the equivalent to be engaged by a stop pin 17 to limit the normal rotation of the door from open to closed position and vice versa, the object of the stop mechanism being to prevent the door from becoming disengaged, otherwise than with the intent of the operator. When, however, as already pointed out, it is desired to remove the door or insert it, the stop pin 17 is withdrawn.

To provide for its normal engagement and its release at the will of the operator or person in charge of the safe, the pin which is mounted to slide into and out of the peripheral edge 18 of the door in a hole or guide 19 which extends through the peripheral face of the door, is urged outwardly into engagement with groove 16 by a coil spring 20 in the hole behind the sliding pin or stop bolt 17 and the 5 sliding pin or stop bolt 17 is provided with a laterally projecting lug or handle 21 which slides in a bayonet slot 22 formed in the back of the door and extending into the hole or guide 19 so that it is out of reach except when 10 the chest door is open. This lug or handle 21 can be engaged by the operator in an obvious manner when the door is open, the operator reaching inside for this purpose and being thus engaged, the stop pin 17 can be withdrawn 15 and locked in withdrawn position by rotating the pin or bolt 17 until the lug or handle 21 moves into the base 24 of the bayonet or L shaped slot 22. When the stop pin or bolt 17 is thus withdrawn, the door being 20 opened and therefore essentially unlocked, it can be rotated oppositely to the direction of closing beyond open position to a position in which it is released and may be removed. 25

As already suggested, the interlocking ribs 30 10 on the door and 8 on the door jamb are discontinued or interrupted at intervals forming rib sections which interlock and hold the door in its seat in all positions to which it can be rotated when the stop pin or bolt 35 17 is advanced engaging the groove 16. The exact length spacing and arrangement of the sections and the form of the interlocking means is capable of wide variations, a preferred arrangement being illustrated in Figure 4, showing the door, and Figure 7 showing the door opening in the chest, the door being removed, and Figures 8 and 15, showing the door in position in the chest.

In accordance with the illustration, Figure 45 4, the rib 10 on the door consists of spaced arcuate outwardly projecting sections. At the top in the closed position of the door is the section 26 which is relatively long, comprising an arc of about 90 degrees, and proceeding around the door in right handed rotation as seen from the rear in Figure 4, next to the rib 26 is a space 27 which is about the same length as rib 26, and next beyond this space is a short rib 28. Next is a space 29 a little shorter than this rib, and beyond the space 29 is a rib 30 shown as a little shorter than the rib 28, next is a space 31 longer than rib 30. Following this is a rib 32 about the length of the space 31 and beyond this is a space 33 of a little less than the length of rib 26. While the spacing in the form of the invention shown has been described, the exact spacing of the ribs and their length is immaterial otherwise than as it contributes 55 to the result and object which is to hold the

door and permit it to be rotated from open to closed position and vice versa, and to permit it to be removed and inserted only when it is rotated to a predetermined position beyond its normal path or normal arc of rotation 70 from open to closed position and vice versa.

Referring now to Figure 7, the inwardly projecting rib 8 on the door jamb comprises in the preferred form of the invention as shown the following arcuate sections suitably spaced, i. e., at the top is a long section 35 of the rib 8 comprising an arc of a length a little less than the length of the space 27 on the door, and proceeding in right handed rotation as the chest is seen in Figure 8, this is followed by a space 36 a little longer than the rib 26 on the door, following which space is a rib 37 a little shorter than the space 33 on the door. Beyond this rib 37 is a space 38 a little wider than the rib 32 on the door and next beyond this space 38 is a short rib 39 a little shorter than space 31 on the door. Beyond the rib 39 is a space 40 a little longer than rib 30 on the door. Beyond this space 40 is a rib 41 a little shorter than space 29 on the door and between the rib 41 and the top rib 35 is a space 42 which is long enough to pass the rib 28 on the door. As pointed out regarding the sections of the rib 10 on the door, the spacing of the sections of the rib 8 on the door jamb may be widely varied, and is only material to the result that the door be held against removal in closed position and in normal open position and throughout the path of rotation from one position to the other. In the form shown the rotation of the door is normally limited to this path or a slightly longer one by means of the removable stop latch 17, but this may be omitted or the result otherwise accomplished within the scope of the invention, the door being preferably capable of rotation when the stop latch is released, to a position in which the sections of the rib 10 on the door are thrown out of contact with the sections of the rib 8 on the jamb and into registration with the spaces between said ribbed sections whereby the door may be removed, or when presented in the same angular position may be inserted. 95

In the construction shown the position of registration is indicated by the comparison of the ribs and spaces on the door and door jamb contained in the description of the door jamb rib sections and spaces. To reach position 100 of registration in which the door may be removed or inserted, the door is rotated counter-clockwise from the closed position, Figure 8, to full open position and the stop 17 having been withdrawn, the door is further rotated 110 in the same direction until space 27 on the door registers with rib section 35 at the top of the door jamb, see Figure 15. In this position the rib sections on each member register 115 with the spaces on the other, permitting the 120

125 130

removal and replacement of the door as aforesaid.

In addition to the stop pin 17, the door is provided with a bolt 45 which slides outwardly beyond the periphery of the door and is controlled by any suitable lock 46 shown as of the combination type. The outer end of the bolt 45 in locked position occupies a keeper slot 47 in the door jamb. There is also a second slot 49 to be engaged by the bolt in the partly open position, Figure 10, in which position the combination of the lock can be changed by means of a pin placed in slot 49'. Hole 49" is also utilized in this connection. In this position of the door the stop 17 can conveniently be reached and withdrawn. The door is also shown as provided with handles or hand grips 48.

The locking bolt 45, the lock 46 and the stop 17 are in the preferred form of the invention shown located in the semicircular half of the door which is at the top in the closed position of Figure 1. This portion of the door overlies a semicircular depression 65 in the rear face of the door and forms the outer wall or base of the same, the exact shape of the depression not being of great importance. By means of this depression the stop member 17 is made easily accessible from the rear while the slot 16 which it engages is near the front. The depression also provides room for the lock 46 without reducing the capacity of the chest and keeps the entire area of the door of the desired normal thickness, avoiding undue weight and expenditure of material, and allows ample thickness at the edges to accommodate the rib 10, the groove 9 and the cylindrical seating surface 62 at the front.

The depression 65 is closed at the side which is at the bottom in the position stated by the diametrical wall or thickened portion 64, which has its rear surface in the rear radial plane or finished rear surface 80 of the door which contacts the forwardly disposed rear-most surface 81 of the jamb, sealing the periphery of the opening 3 at all points in the closed position, Figure 1.

In the conduct of chain stores and oil stations, it is desirable to have the chest or safe so arranged that the collections may be deposited in each individual safe by the employees of the store in which it is located, the employees being, however, barred from access to the safe in a manner which would enable them to remove the contents, the money being subsequently removed by an employee who acts as collector for the organization and has sole access to the contents of the safes of the entire chain or a considerable portion of it for this purpose. To this end, the present structure may be provided with a second or inner door 50 which closes the door opening 3 inside the main or chest door, the inner door 50 being held in closed position by a suitable

type of key lock 51 to which the collector referred to will carry the key and by suitable tenons 59 fitting in slots 60. This door in the form of the invention shown is semi-circular, fitting the door opening 3 which is finished with a peripheral seat 52 to receive the door, the seat being slotted at the bottom to admit any suitable tongues or projections or edge portions 53 at the bottom of the door, the door being then swung into position and secured by means of the lock 51. This lock is shown as having a bolt 54 which enters a keeper 55 formed in or secured to the body of the chest wall. To provide for the deposit in the safe of the money as collected, the inner door 50 is slotted at 56 or the safe may be provided with a chute 57 for the admission to the inner compartment 58 of envelopes or packages of money or other valuables. This latter is in accordance with the practice in moving picture houses in which the safe is placed below the ticket window so that the money can be packaged and dropped into the safe as and when a sufficient quantity is collected.

In Figures 13 and 14 I have shown a slightly modified construction providing for double custody, the inner door 66 in this instance being arranged horizontally and opposite or slightly below the bottom of the chest door opening 3, the inner door 66 with its frame 67 and the supporting lip therefor 68, which is formed on the inside of the chest body 1, for this purpose, comprising a horizontal partition which divides the inside of the chest into an upper chamber 69, which is immediately accessible through the door opening 3 and a lower chamber 70, which is accessible only from the upper chamber 69 by way of the inner door 66, or, more properly, the inner door opening 71, which is closed thereby. The inner door 66 is shown as provided with a slot 72 for the admission of envelopes, and similar packages of money and the like and is secured in any suitable manner as by means of a lock 73 which is preferably of the key type, having a bolt 74, which enters a suitable keeper slot 75 at one side of the door jamb or groove 76 in the frame 67, in which the door rests, the door having at the other side a suitable tongue or tenon 77, which enters a corresponding slot 78 in the door frame.

The manner of using and operating the chest and particularly the chest door has been quite fully explained in connection with the description of the structure. Assuming that the chest door 4 has been removed and is to be placed in position, it is engaged by the handles 48 and inserted in the jamb 5, being rotated to the position in which the sections of the rib 10 on the door register with the spaces between the sections of the rib 8 on the jamb as indicated in Figure 15. In this position the stop 17 and the bolt 45 being withdrawn, the stop pin 17 being held in

withdrawn position by inserting the lug 21 in the notch 24 of slot 22 and the bolt 45 being held by the action of the lock 46, the door is pushed rearwardly, i. e. to the right in Figure 1, until the sections of the rib 10 thereon pass the sections of the rib 8 in the jamb and enter the groove 7 in the jamb when the door can best be rotated to the position shown in Figure 10, in which position the stop or stop pin 17 may be released and allowed to enter the stop groove 16. The bolt 45 may be caused to enter the slot 49 as a convenient means for locating the door in this position. When the stop 17 has been released and allowed to move by expansion of the spring 20, to operative position, the bolt 45 being withdrawn, the door may be rotated to closed or to full open position to suit the convenience of the operator, being locked in closed position by the entrance of the bolt 45 into the keeper slot 47, the door opening 3 being preferably eccentric as to the jamb and door and the aperture 12 in the door being likewise preferably eccentric as shown. The opening 3 is uncovered and the chest is opened by rotating the door to a position in which the opening 3 and aperture 12 are in registration and the chest door is closed by rotating to place the aperture 12 completely out of registration and out of alignment at all points with the opening 3. To give the desired protection for the contents of the safe and to avoid cracks and openings between the door and the door jamb, which would be a source of weakness in case of an attempt to crack the safe, the surfaces of the grooves and ribs 7, 8, 9 and 10 are preferably finished and suitably fitted likewise the cylindrical outer surfaces 61—62 of the jamb and door, the rear surface 80 of the door and the forwardly disposed rear surface 81 of the door jamb providing a close fit as to the meeting surfaces which contributes to the closing and guarding of the door opening 3 in the closed position of the safe. The use of the inner door 50, Figure 1, permitting the insertion of envelopes or similar packages of money or the like through the slot 56 to be retained in the safe, said packages being only accessible to the person, presumably the authorized agent of the owner, having possession of the key, the lock 51 being shown as a key lock, though any suitable lock may be used within the scope of the invention, has been fully explained. The door is shown as anchored to prevent removal from the safe by means of a chain 83.

The use of the construction, Figures 13 and 14, is similar except that the contents of the upper chamber 69 is accessible to all those having access to the safe for any purpose while the lower compartment into which packages and envelopes may be introduced by way of a slot 72 is closed by a separate lock, usually a key lock, so that the contents

may be handled by a collector or other person duly authorized.

I have thus described specifically and in detail, preferred and slightly modified forms of a chest and door structure embodying my invention in order that the manner of constructing, operating and using the same may be fully understood, however, the specific terms herein are used descriptively rather than in a limiting sense, the scope of the invention being defined in the claims.

What I claim as new and desire to secure by Letters Patent is:

1. In a chest having a circular seat, a door opening which is eccentrically located within the seat, and a compartment of a cross sectional area substantially larger than the door opening and substantially coaxial with said seat, a door having a rotary engagement with the seat and having an aperture which is also eccentric and adapted to be moved into and out of alignment with said opening thereby opening and closing the same by rotation of the door, and means for locking the door against rotation.

2. In a chest a chest body having a circular seat and a door opening which is eccentrically located as to the seat, a door having a rotary engagement with the seat and having an aperture which is also eccentric and adapted to be moved into and out of alignment with said opening, opening and closing the same by rotation of the door, means for locking the door against rotation, a removable stop limiting the rotation of the door but permitting it to be moved from open to closed position and vice versa, interengaging means on the door and safe body guiding and holding the door in operative relation to the seat and providing for such rotation, the same having a point of disengagement reached when the door is rotated to a predetermined point beyond the arc of rotation permitted by the stop when in engagement.

3. The combination in a chest of a circular door jamb and a wall partially closing the jamb, providing an eccentric door opening of less area than the door jamb, a door mounted to rotate in the jamb and having an aperture eccentrically located and adapted to be moved by rotation of the door into and out of registration with the door opening to open and close the door, means for locking the door to prevent rotation thereof, the door and jamb having peripheral contacting surfaces and peripheral interengaging ribs, said ribs being spaced to release the door in a certain position and means normally restraining the door from reaching said position of release.

Signed by me at York, Pennsylvania, this 14th day of February, 1928.

CHARLES F. SIOBERG.
